UNITED STATES PATENT OFFICE.

HENRY JOHN MEYERS, OF LOS ANGELES, CALIFORNIA.

BED-MOUNTING.

1,262,371.

Specification of Letters Patent.

Patented Apr. 9, 1918.

Application filed August 14, 1916. Serial No. 114,920.

To all whom it may concern:

Be it known that I, HENRY J. MEYERS, a citizen of the United States, residing at Los Angeles, in the county of Los Angeles and State of California, have invented new and useful Improvements in Bed-Mountings, of which the following is a specification.

This invention relates to a folding bed construction and particularly pertains to a detachable pivot bed.

It is an object of this invention to provide means whereby a folding bed may be pivotally mounted to swing through an opening into and from a closet and which is detachably secured upon its mounting so that it may be removed therefrom and moved to remote parts of a room.

Another object of this invention is to provide adjustable means incorporated within the pivotal mounting whereby the bed may be raised and lowered in relation to the floor and may be held to swing over the floor without bearing thereupon.

Another object is to provide a bed of light construction which is adapted to be folded into a small space and which, when unfolded, will possess considerable strength.

Another object is to provide a special pivotal foot-board mounting which may be readily swung to its folded position and which, when so swung, will act in a telescoping manner to allow the bed to pass through door openings of ordinary height.

A further object is to provide a bed and mounting of the above class which may be readily set up in its operative position and which requires no alteration of door casings or other construction to allow it to be used.

Other objects will appear hereinafter.

The invention is illustrated in the accompanying drawings in which:

Figure 1 is a view in side elevation illustrating the pivot bed as in its unfolded position.

Fig. 2 is a view in horizontal section illustrating a closet and showing the bed folded therein.

Fig. 3 is a view similar to Fig. 2 and illustrates the bed in its outermost position after having been swung through the closet opening.

Fig. 4 is a view in section and elevation as seen on the line 4—4 of Fig. 1 and illustrates the bed construction.

Fig. 5 is an enlarged view showing the

end of the side rails of the bed and the manner in which the foot-board is pivotally mounted thereupon and further showing in dotted lines an intermediate position of the 60 foot-board.

Fig. 6 is a view of the hinge member by which the foot-board is pivoted and is drawn on a reduced scale.

Fig. 7 is a view in horizontal section as 65 seen through one of the posts of the foot-board on the line 7—7 of Fig. 5.

Fig. 8 is a view of the pivotal mounting provided the bed.

Fig. 9 is a view in diagram illustrating 70 the manner of positioning the bed within the closet of greater depth than width.

Fig. 10 is a view similar to Fig. 9 illustrating the bed as in its outermost position.

Fig. 11 is a view corresponding to the preceding view, illustrating the bed as detached from its mounting.

Referring more particularly to the drawings, 10 indicates the head-board of a bed and is here shown as being mounted upon 80 a suitable structural base 11. The ends of the base 11 are formed of plates 12 which have arcuate slots 13 formed through them. The slots are described on an arc from the center of pivot pins 14 to which links 15 85 are secured and the ends of which are pivotally secured to the plates adjacent the termination of the slots and at their lower ends. Pins 16 are suitably secured to a point adjacent the ends of side rails 17 and 90 are guided through the slots 13 as the main frame of the bed is raised and lowered. In order to facilitate in raising the bed and to partially counterbalance the weight thereof as it is being lowered, a series of coil springs 95 18 are secured by their one ends to a cross rail 19 of the base and by their other ends to a cross rail secured upon the bed frame at a point in the rear of the fulcrum pins 14, thereby producing a partial counterbalance of the bed frame and the clothing thereon. The opposite ends of the bed rails are fitted with specially formed hinges which each have one straight leaf 20 secured to the frame and a movable leaf 21 100 secured to the frame and a movable leaf 21 pivoted thereto. The movable leaf 21 is of peculiar configuration in that it is formed with an internal dove-tail slot 22 throughout its length adapted to be swung into register with a similar dove-tail portion 23 secured 105 to the end of the frame. These dove-tail slots are adapted to be engaged by dove.

Fig. 12 is a view in section and elevation as seen on the line 12—12 of Fig. 11 and illustrates the hinge member.

tails 24 which are secured to the vertical posts 25 of the foot-board 26.

The bed, as described, is pivotally mounted by means of a removable pivot pin 27 to a pivot block 28 which is formed with a pair of vertically disposed ears 29 and 30 through which the pin passes and which register with ears 31 and 32 secured to the frame 11 of the bed. As particularly shown 10 in Fig. 8 of the drawings, the pivot block is further provided with a single fixed pivot pin 33 which is secured to the floor by a flange 34. This pin is engaged by an ear 35 formed upon the pivot block and upon 15 which the entire bed is adapted to swing. As a means for adjusting the distance between the bed and the floor the pivot pin 33 is externally threaded and is provided with a nut 36 which is adapted to support the 20 pivot block 28 and also the weight of the bed. A lock nut 37 is secured to the upper end of the pivot pin and above the ear 35. It will thus be seen that by adjusting the 25 nuts 36 and 37 the bed may be raised to relieve its weight from the floor when folded and thus prevent highly polished floors from being marred by the movement of the bed thereover in swinging the bed in and out of the closet. The nut 36 may be screwed 30 down to lower the bed when it is desired to detach the latter and move it to a point remote from the pivot at which time the bed will rest on casters.

In the operation of this bed, it will be 35 assumed that the bed is initially within the closet 38, as particularly shown in Fig. 2. It is evident, however, that the exact position of the bed as there shown is not the only position the bed might assume as in 40 longer closets the pivot block may be swung a half turn farther and will thus allow the bed to be removed to a partial obstructing position before the closet door. When the bed is swung outwardly it will pass through 45 the closet opening as permitted by the pivot block 28 and will assume the position indicated in Fig. 3 of the drawings. The bed is now ready to be unfolded and this may now be accomplished by drawing it downwardly 50 upon the support of its links 15 and by the added support of the pivot pins 16 as they travel along their arcuate slots 13. When the foot-board of the bed has been drawn within reach it may be swung outwardly at 55 right angles to the side rails 17 and the dovetails secured to the posts of the board forced upwardly through the hinge member 22 and the fixed internal dove-tail 23. The sides

of the internal dove-tails are tapered so that as the member 24 is wedged therein the 60 foot-board will be secured in a rigid manner and against pivotal movement.

It may be necessary to utilize a closet disposed in relation to the wall as indicated in Figs. 9, 10 and 11 of the drawings. In such 65 a case the pivot block is positioned a distance within the closet and near one side thereof. The bed, when swung outwardly, may be made to assume the position indicated in Fig. 10 and when so positioned is 70 adapted to be removed from its pivotal mounting and moved to other parts of the room, thus allowing the closet door to be closed and the appearance of the room to be the same as though beds of ordinary construction were used.

When the bed is to be moved to other parts of the room the pivot pin 27 is withdrawn from the ears on the bed frame and the pivot block with which it registers and 80 thus the bed will be permitted to roll upon casters 39 suitably secured beneath the bed posts. Should the bed be elevated on the pin 33 so as to cause the pivot pin 27 to bind, the nut 36 is lowered so that strain on 85 the pin is relieved to permit its ready removal. In this manner the bed is provided with easily operated means for positioning it within a closet and through an opening and at the same time allowing it to be placed 90 within the room at any point of vantage as required.

It will thus be seen that the pivot bed here disclosed is simple in its operation and may be easily installed for use without alteration of various parts or the necessity of 95 special building construction.

I claim:

1. In a bed construction, a bed base, a pivot block adapted to be pivotally and detachably secured to said base, a fixed pivot around which said block is afforded horizontal movement and adjustable means whereby the bed base may be raised and lowered in relation to the floor.

2. A swinging bed mounting comprising a base plate, a threaded stem thereon, a pivot block turnable and vertically adjustable on said pin, a pair of nuts screwed on said threaded stem on opposite sides of the pivot 110 block at its point of engagement with the stem, a bed frame, and a pivot pin connecting said bed frame to said pivot block.

In testimony whereof I have signed my name to this specification.

HENRY JOHN MEYERS.
